CLAIM

The ornamental design of a fire log, as shown and described.

DESCRIPTION

FIG. 1 is a perspective view of a fire log according to the present invention;

FIG. 2 is a side elevation view of the log, the opposite side being a mirror image;

FIG. 3 is a frontal elevation of the log shown in FIG. 1;

FIG. 4 is a top elevation of the log shown in FIG. 1;

FIG. 5 is a bottom elevation of the log shown in FIG. 1; and,

FIG. 6 is a top view of an alternative embodiment of the log, the difference residing in a provision of one channel instead of two.
